[57] CLAIM

The ornamental design for a bottle and cover, as shown and described.

DESCRIPTION

FIG. 1 is a front elevational view of a bottle and cover embodying my design, while a rear elevational view would be a mirror image of FIG. 1;

FIG. 2 is a right side elevational view of FIG. 1, while a left side elevational view would be a mirror image of FIG. 2;

FIG. 3 is a top plan view of FIG. 1; and,

FIG. 4 is a bottom plan view of FIG. 1.

FIG. 1

FIG. 2

FIG. 3

FIG. 4
